UNITED STATES PATENT OFFICE.

GEORGE STECK, OF NEW YORK, N. Y.

PIANO.

SPECIFICATION forming part of Letters Patent No. 367,073, dated July 26, 1887.

Application filed June 3, 1887. Serial No. 240,130. (No model.)

To all whom it may concern:

Be it known that I, GEORGE STECK, of New York city, New York, have invented a new and Improved Piano, of which the following 5 is a specification.

The invention relates to various improvements on stringless pianos.

It consists in the features of construction more fully pointed out in the claims.

10 In the accompanying drawings, Figure 1 is a vertical transverse section on line *xx*, Fig. 2. Fig. 2 is a horizontal section on line *yy*. Fig. 1. Fig. 3 is a detail perspective view of the plate *d*; and Fig. 4 is a detail longitudinal section through the socket *e*.

15 The letter *a* represents the square frame of a piano containing a suitable action, *b*, having hammer *b'*, and operated by key *c*, as usual. Against the back plate of the frame *a* there is 20 placed an upright metal plate, *d*, having a horizontal flange, *d'*, as shown. The plate *d* extends about half-way across the piano, from right to left, and is secured in place by being tightly screwed to the frame *a*. Upon the 25 flange *d'* there are placed at short intervals, and secured by screws or otherwise, a number of sockets, *e*. Each of these sockets carries the end of a coiled spring, *f*, the coils of each spring being placed in substantially parallel 30 layers, as shown. The plate *d* constitutes in substance a sounding-board; but the instrument is provided with an additional horizontal sounding-board, *g*, which is placed at a short distance from the flange *d'*, and approximately 35 in line with it. Between the flange *d'* and the sounding-board *g* the springs *f* have but a single coil, *f'*, as shown, while directly above the sounding-board *g* the springs are coiled 40 several times backward and forward. The portion *f'* of the spring *f* is the one acted upon by the hammer *b'* from below, and also by a damper, *h*, from above. This damper is secured to a lever, *h'*, pivoted to damper-frame at *h*, and adapted to be oscillated from key *c* 45 by means of a lifter, *h*. This lifter passes through a perforation, *h*, of flange *d'*, Fig. 3, the several perforations *h* for the several damper-lifters being placed in front of sockets *e*, and between the springs *f*, as shown.

As thus far described the piano is constructed 50 to produce the lower notes, and this construction extends to about the center of the piano. The right-hand or higher notes are not produced by the coiled springs *f*, but by a number of straight metal plates, *i*, which are 55 capable of a limited up and down motion, and which are secured to the sounding-board *g*, so as to project with their rear end over the rear edge of the sounding-board. Thus the plates *i* are accessible to the hammers *b'*.

Of course the length of the springs *f* and also the length of the plates *i* varies, as shown, decreasing from low to high notes.

A piano constructed as described will be found to possess a full and clear tone. It may 65 be strongly and at the same time cheaply manufactured.

What I claim is—

1. The combination of sounding-board *d*, having flange *d'*, and of sounding-board *g*, with 70 the springs *f*, having a single coil between the parts *d*, *g*, and double coils above sounding-board *g*, substantially as specified.

2. The combination of sounding-board *d*, having perforated flange *d'*, with the sockets *e* 75 and springs *f*, and with the dampers *h*, connected to the levers *h'*, and with the damper-lifters *h*, passing through perforations *h* of flange *d'*, substantially as described.

3. The combination of the upright sounding-board *d*, having flange *d'*, and of the horizontal sounding-board *g*, with the springs *f*, secured to flange *d'*, and with the hammers *b'* and dampers *h*, acting upon springs *f* between the flange *d'* and sounding-board *g*, substantially as specified.

4. The combination of sounding-board *d*, having flange *d'* and carrying springs *f*, with the sounding-board *g*, extending beneath the forward ends of such springs, and with the 90 vertically-movable plates *i*, projecting beyond the rear edge of sounding-board *g*, substantially as specified.

GEORGE STECK.
